Primary Examiner — Derrick E Holland*Assistant Examiner* — Jennifer O King*(74) Attorney, Agent, or Firm* — Ryan Liebengood(57) **CLAIM**

I claim the ornamental design for a corner cable conduit, as shown and described.

DESCRIPTION

FIG. 1 is a perspective view of a corner cable conduit showing my design;

FIG. 2 is a left side view thereof;

FIG. 3 is a right side view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines shown in the Figures represent portions of the corner cable conduit that form no part of the claimed design.
